W. F. MOODY.
Corner-Fastening for Connecting Bed-Bottom Frames, &c.
No. 224,028. Patented Feb. 3, 1880.

ATTEST.

Octave Delcourt*

INVENTOR.

William F. Moody

UNITED STATES PATENT OFFICE.

WILLIAM F. MOODY, OF CHICAGO, ILLINOIS.

CORNER-FASTENING FOR CONNECTING BED-BOTTOM FRAMES, &c.

SPECIFICATION forming part of Letters Patent No. 224,028, dated February 3, 1880.

Application filed August 13, 1879.

To all whom it may concern:

Be it known that I, WILLIAM F. MOODY, of Chicago, in the county of Cook and State of Illinois, have invented a new and useful Im-

5 provement in Corner-Fastenings for Connecting the Frames of Bed-Bottoms and for Stretching the Fabric; and I do hereby declare the following to be a full, clear, and exact description of the same, reference being had to the accompanying drawings, making a part of this specification, in which—

Figure 1 represents a portion of a side and end rail of a bed-bottom secured with my improved corner-fastener. Fig. 2 represents a 15 side view of the long rail and a section of the fastener and cross-rail with fabric in position; Fig. 3, an end view of the fastening removed from the rails; Fig. 4, a transverse section of the long rail, and a broken longitudinal section of the short rail, taken on line *x*, Fig. 2. Figs. 5 and 7 are broken perspectives of the 20 two-part end rail; Fig. 6, a plan view of the fastener removed from the other parts. Fig. 25 8 is an enlarged representation of the nuts and bolts by which the fabric is stretched and the rails and fastener united.

Like letters of reference indicate like parts.

The invention consists, first, in the combination of a corner-casting and nut of peculiar construction, hereinafter fully described, of the adjusting screw-bolt and holding-screw; and, second, of the combination of said nut with said bolt and screw.

35 B represents the side rail; and C C the two-part end rail of a wire-mattress bed-bottom.

The fastening-casting is shown at A, which consists of a solid exterior flat side and a solid interior end, 2, with flanges H I projecting inward to form a socket between a skeleton-partition, 3, and the top of the casting, to receive

and support the two-part end rail, C C. The rail C C is held endwise in said socket by means of a tongue, 4, on the casting fitting into a groove, 5, in said end rail. 45

Projecting down from the lower plate of the casting A are flanges 6, which pass on to the sides of the side rail, to guide the casting in its movement thereon and hold the frame square. 50

D represents a nut, which is provided with a shank, 7, which is tapped into the end rail, B, as shown by dotted lines, Fig. 2. In the lower end of this shank is cut a screw-thread to form a nut for screw G, which passes from the under side of the rail B into shank 7, to draw the shoulders 8 of nut D onto plate E, to clamp the casting fast to the frame. 55

An adjusting-bolt, F, is put through the end 2 of the casting and into nut D, and is turned 60 in the ordinary manner to tighten the fabric 10, a slot, 11, in the plate E allowing the casting to have a proper movement for that purpose.

I claim as new and desire to secure by Letters Patent of the United States— 65

1. The single casting formed with solid side A, solid end 2, partition 3, flanges H I, tongue 4, flanges 6 6, and recess between the partition 3 and the bottom plate, E, in combination 70 with the adjusting-bolt F, nut D, provided with shoulders 8, screw-bolt F, and screw G, as specified.

2. The nut D, provided with the shoulders 8, for clamping the plate E to the side rail, in 75 combination with the screw-bolt F and the screw G, as specified and shown.

WILLIAM F. MOODY.
